(57) **CLAIM**

The ornamental design for a device for musical instrument practice, as shown and described.

DESCRIPTION

FIG. 1 is a perspective view of a device for musical instrument practice showing my new design;
FIG. 2 is a front elevation view thereof;
FIG. 3 is a rear elevation view thereof;
FIG. 4 is a left side view thereof;
FIG. 5 is a right side view thereof;
FIG. 6 is a top plan view thereof; and
FIG. 7 is a bottom plan view thereof;
FIG. 8 is a perspective view showing the design of the device for musical instrument practice in a usage condition; and,
FIG. 9 is a perspective view showing the design of the device for musical instrument practice in a usage condition. The broken line portion of the figure drawings is included to show unclaimed subject matter only and forms no part of the claimed design.
